(57) **CLAIM**

The ornamental design for a cell phone mounting bracket, as shown and described.

DESCRIPTION

FIG. 1 is a perspective view of my design in a first configuration;

FIG. 2 is a front view thereof;

FIG. 3 is a back view thereof;

FIG. 4 is a left side view thereof;

FIG. 5 is a right side view thereof;

FIG. 6 is a top view thereof;

FIG. 7 is a bottom view thereof;

FIG. 8 is a perspective view of my design in a second configuration;

FIG. 9 is a front view of my design in the second configuration;

FIG. 10 is a back view of my design in the second configuration;

FIG. 11 is a left side view of my design in the second configuration;

FIG. 12 is a right side view of my design in the second configuration;

FIG. 13 is a top view of my design in the second configuration;

FIG. 14 is a bottom view of my design in the second configuration;

FIG. 15 is a perspective view of my design in a third configuration;

FIG. 16 is a front view of my design in the third configuration;

FIG. 17 is a back view of my design in the third configuration;

FIG. 18 is a left side view of my design in the third configuration;

FIG. 19 is a right side view of my design in the third configuration;

FIG. 20 is a top view of my design in the third configuration;

FIG. 21 is a bottom view of my design in the third configuration;

FIG. 22 is a perspective view of my design in a fourth configuration;

FIG. 23 is a front view of my design in the fourth configuration;

FIG. 24 is a back view of my design in the fourth configuration;

FIG. 25 is a left side view of my design in the fourth configuration;

FIG. 26 is a right side view of my design in the fourth configuration;

FIG. 27 is a top view of my design in the fourth configuration; and,

FIG. 28 is a bottom view of my design in the fourth configuration.

Broken lines illustrate portions of the cell phone mounting bracket that form no part of the claimed design.
